UNITED STATES PATENT OFFICE.

CHARLES W. DAKE, OF GRAND RAPIDS, MICHIGAN, ASSIGNOR TO THE DAKE-AMERICAN STEAM TURBINE COMPANY, OF GRAND RAPIDS, MICHIGAN, A CORPORATION OF MICHIGAN.

ELASTIC-FLUID GENERATOR.

No. 897,354.

Specification of Letters Patent.

Patented Sept. 1, 1908.

Application filed April 10, 1907. Serial No. 367,463.

To all whom it may concern:

Be it known that I, CHARLES W. DAKE, a citizen of the United States, residing at the city of Grand Rapids, county of Kent, State of Michigan, have invented certain new and useful Improvements in Elastic-Fluid Generators, of which the following is a specification.

This invention relates to improvements in generators.

My improved generator is particularly designed by me for converting a dense fluid into an elastic fluid for the driving of engines, although it is desirable for use in various other relations, as for heating purposes.

The main objects of this invention are, first, to provide an improved generator of the class described which is highly efficient and economical in the production of elastic fluid. Second, to provide an improved generator of the class described which is compact and economical in structure and not likely to get out of repair in use.

Further objects, and objects relating to details of construction, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which,

Figure 1 is a central vertical section of a structure embodying the features of my invention; Fig. 2 is a horizontal section taken on a line corresponding to the broken line 40 S—S of Fig. 1, portions only of the coil being sectioned; Fig. 3 is a side elevation of the superheating cone 2; and Fig. 4 is an inverted plan of the cap 3, the cone 5 being shown in transverse section.

In the drawing, the sectional views are taken looking in the direction of the little arrows at the ends of the section lines, and similar numerals of reference refer to similar parts throughout the several views.

Referring to the drawing, 1 is a casting from which the parts of the generator are supported. This casting 1 is provided with a delivery chamber 22 for the elastic fluid, and also with a delivery passage 24 for the delivery chamber. The casting 1 is also

preferably provided with a supporting flange 25 by which it may be connected to an engine, if desired. Below the casting 1 is an inverted conical superheating chamber 2 having an outwardly-projecting flange at its upper end adapted to rest on an annular flange provided therefor in the casting 1. The walls of the superheating chamber 2 are preferably spirally-corrugated to form a spiral groove 2'. The superheating chamber is clamped by a threaded member 3, which has an opening 21 therein connecting the superheating chamber to the delivery chamber 22. Within the superheating chamber is an inverted baffle cone 5 opening at its lower end and connected at 70 its upper end to the clamping member 3. The delivery chamber is provided with a cap or cover 4.

About the cone 1 I arrange the heating coils 6, which are connected at their delivery end 6² to the passage 18, which is in turn connected to the annular passage 19 formed in the clamping member. This passage 19 is connected by a plurality of ports 20 to the superheating cone, the ports 20 opening into 80 the superheating chamber outside of the baffle cone 5, so that any fluid passing through these ports must pass down the walls of the superheating cone to the lower end thereof before entering the delivery 85 chamber 22 through the baffle cone. The fluid to be converted is conducted to the coils through the pipe 6'.

Arranged below the superheating chamber is a burner, the burner illustrated being 90 designed for burning gasoline, alcohol, or the like. The fuel supply pipe 9 is coiled about the burner above the fuel cup 14 and about the upper end of the burner tube 7, and connected to the inlet passage 10 in the body 11 95 of the burner. The burner is provided with a needle valve 8', the stem 8 of which projects downwardly for convenience in manipulation. A suitable packing gland, as 15, is provided for the valve stem.

In starting the burner, the valve 8' is opened, when the liquid fuel will flow down through the passages 37 into the generating cup 14 of the burner. The fuel is ignited in this cup and gas is generated in the supply 100 pipe, which is coiled above the burner cup, as stated, and in the base of the burner. The burner is provided with a burner tube 7 having a plurality of air inlet openings 12. The burner tube is arranged through the bottom 110

29 of the main casing with its air ports 12 below the bottom, the burner tube being preferably threaded through the bottom. The inlet ports 12 are provided with a suitable sleeve-like valve 13. In the side of the casing 35 for the burner is an opening 16 provided with a suitable door 17 through which the fuel in the burner cup 14 may be ignited. The door 17 is preferably in the 10 form of a sleeve surrounding the base of the casing, it being secured in position thereon by rivets 17' arranged through suitable slots therein.

The generating coils and the burner are 15 surrounded by a casing preferably double walled, consisting of an outer casing 27 and an inner casing 28, between which is a suitable insulating material 32, such as asbestos or mineral wool, for preventing the cold air 20 striking the generating coils and superheating chamber; and also for preventing radiation of the heat. At the top of the casing is a chimney or flue 33 for carrying off the products of combustion.

25 The chamber 22 is preferably provided with a safety valve 26 which delivers into the flue 33. The safety valve 26 is preferably a poppet valve, held in position by a suitable spring, the same being seated in the 30 outer end of the passage 23.

The upper part of the casing is preferably made detachable and is preferably arranged on the lower part like a cover, so that it may be removed to afford ready access to 35 the interior. The casing is provided with an opening 30, through which the burner may be ignited. This opening is provided with a suitable door 31.

In operation, the fuel, which may be gasoline, alcohol, or other inflammable material, 40 is admitted to the burner through the valve 8'. The fuel will run out into the burner tube and down through the hole 37 into the generating cup 14. The valve is then closed 45 and the fuel in the cup ignited. This heats the supply tube 9, which is coiled above the cup, and the base of the burner, as described, converting the liquid fuel therein into a gas. The needle valve is then opened and the gas 50 flows up through the burner tube 7, drawing in sufficient air to make a proper burning mixture through the openings or air ports 12. The flame from the burner surrounds the generating chamber 2, heating it to a 55 very high temperature. The coils 6 also become very hot. When the whole is sufficiently hot, the denser fluid, such as water, is forced up through the coils 6 to the superheating chamber. The fluid is at this time 60 converted or almost converted into an elastic fluid. The generating cone, being very hot, the fluid, by passing downwardly over this to the lower end of the baffle cone, is converted into a superheated elastic fluid, in which condition it passes up through the baffle cone 65

into the delivery chamber 22 and thence is delivered to the engine, or for any other desirable purpose.

The superheating cone is, as before described, provided with spiral grooves, so that, should the denser fluid not be converted into an elastic fluid before entering the superheating chamber, it will run down the spiral groove and in so doing be converted.

My improved generator is very efficient 75 and economical to operate. It is also simple and economical in structure, being very compact, and the parts being readily assembled.

I have illustrated and described my improved generator in detail in the form preferred by me on account of its structural simplicity and economy and the convenience in use. I am aware, however, that it is capable of very great variation in details of construction without departing from my invention, 85 and I desire to be understood as claiming the same specifically as illustrated, as well as broadly.

Having thus described my invention, what I claim as new and desire to secure by Letters 90 Patent is:

1. The combination with a casing having a closed bottom and having a discharge flue at its upper end, of a supporting casting arranged in the upper end of said casing, said casting comprising a discharge chamber; an inwardly-projecting annular flange at the bottom of said discharge chamber; a cap for said discharge chamber; a safety valve therefor carried by said cap; an inverted conical 100 superheating chamber having an outwardly-projecting flange at its upper end arranged on said flange in said discharge chamber, said superheating chamber being adapted to be removed through the top of said discharge 105 chamber; a threaded member for clamping said superheating chamber in position, said threaded member being provided with an opening for connecting said superheating chamber to said discharge chamber, and with an annular delivery passage; a plurality of ports connecting the said delivery passage to said superheating chamber; an inverted conical baffle open at its lower end, carried by said threaded member and projecting 110 downwardly into said superheating chamber; heating coils arranged about said superheating chamber and connected to deliver to said annular delivery passage; a burner arranged below said superheating chamber, the burner tube of said burner being threaded through the bottom plate of said casing; and a casing 120 for said burner.

2. The combination with a casing, of a supporting casting arranged in the upper end of said casing, said casting comprising a discharge chamber; an inwardly-projecting annular flange at the bottom of said discharge chamber; a cap for said discharge chamber; a safety valve therefor carried by 130

- 6 said cap; an inverted conical superheating chamber having an outwardly-projecting flange at its upper end arranged on said flange in said discharge chamber, said superheating chamber being adapted to be removed through the top of said discharge chamber; a threaded member for clamping said superheating chamber in position, said threaded member being provided with an opening for 10 connecting said superheating chamber to said discharge chamber, and with an annular delivery passage; a plurality of ports connecting the said delivery passage to said superheating chamber; an inverted conical baffle open at its lower end, carried by said threaded member and projecting downwardly into said superheating chamber; and heating coils arranged about said superheating chamber and connected to deliver to said 15 annular delivery passage.
- 7 3. The combination with a casing having a closed bottom and having a discharge flue at its upper end, of a supporting casting arranged in the upper end of said casing, said casting comprising a discharge chamber; an inwardly-projecting annular flange at the bottom of said discharge chamber; a cap for 20 said discharge chamber; a safety valve therefor carried by said cap; an inverted conical superheating chamber having an outwardly-projecting flange at its upper end arranged on said flange in said discharge chamber, said superheating chamber being adapted to be removed through the top of 25 said discharge chamber; a threaded member for clamping said superheating chamber in position, said threaded member being provided with an opening for connecting said superheating chamber to said discharge chamber, and with an annular delivery passage; a plurality of ports connecting the said delivery 30 passage to said superheating chamber; an inverted conical baffle open at its lower end carried by said threaded member and projecting downwardly into said superheating 35 chamber; heating coils arranged about said superheating chamber and connected to deliver to said annular delivery passage; a burner arranged below said superheating 40 chamber, the burner tube of said burner being threaded through the bottom plate of said casing; and a casing for said burner.
- 4 4. The combination with a casing, of a supporting casting arranged in the upper end of said casing, said casting comprising a discharge chamber; an inwardly-projecting annular flange at the bottom of said discharge chamber; a cap for said discharge chamber; a safety valve therefor carried by said cap; an inverted conical superheating chamber having an outwardly-projecting flange at its upper end arranged on said flange in said discharge chamber, said superheating chamber being adapted to be removed through the top of 50 said discharge chamber; a threaded member for clamping said superheating chamber in position, said threaded member being provided with an opening for connecting said superheating chamber to said discharge chamber, and with an annular delivery passage; a plurality of ports connecting the said delivery passage to said superheating chamber; an inverted conical baffle open at its lower end, carried by said threaded member and projecting downwardly into said superheating chamber; and heating coils arranged about said superheating 55 chamber and connected to deliver to said annular delivery passage.
- 5 5. The combination with a casing having a closed bottom and having a discharge flue at its upper end, of a supporting casting arranged in the upper end of said casing, said casting comprising a discharge chamber; an inwardly-projecting annular flange at the bottom of said discharge chamber; an inverted conical superheating chamber having an outwardly-projecting flange at its upper end arranged on said flange in said discharge chamber, said superheating chamber being adapted to be removed through the top of said discharge chamber; a threaded member for 60 clamping said superheating chamber in position, said threaded member being provided with an opening for connecting said superheating chamber to said discharge chamber, and with an annular delivery passage; a plurality of ports connecting the said delivery passage to said superheating chamber; an inverted conical baffle open at its lower end, carried by said threaded member and projecting downwardly into said superheating chamber; and heating coils arranged about said superheating 65 chamber and connected to deliver to said annular delivery passage.
- 6 6. The combination with a casing, of a supporting casting arranged in the upper end of said casing, said casting comprising a discharge chamber; an inwardly-projecting annular flange at the bottom of said discharge chamber; an inverted conical superheating chamber having an outwardly-projecting flange at its upper end arranged on said flange in said discharge chamber, said superheating chamber being adapted to be removed through the top of said discharge chamber; a threaded member for clamping said superheating chamber in position, said threaded member being provided with an opening for connecting said superheating chamber to said discharge chamber, and with an annular delivery passage; a plurality of ports connecting the said delivery passage to said superheating chamber; an inverted conical baffle open at its lower end, carried by said threaded member and projecting downwardly into said superheating chamber; and heating coils arranged about said superheating 70 chamber and connected to deliver to said annular delivery passage.
- 7 7. The combination with a casing having a closed bottom and having a discharge flue at its upper end, of a supporting casting ar- 75

- ranged in the upper end of said casing, said casting comprising a discharge chamber; an inwardly-projecting annular flange at the bottom of said discharge chamber; an inverted conical superheating chamber having an outwardly-projecting flange at its upper end arranged on said flange in said discharge chamber, said superheating chamber being adapted to be removed through the top of said discharge chamber; a threaded member for clamping said superheating chamber in position, said threaded member being provided with an opening for connecting said superheating chamber to said discharge chamber, and with an annular delivery passage; a plurality of ports connecting the said delivery passage to said superheating chamber; heating coils arranged about said superheating chamber and connected to deliver to said annular delivery passage; a burner arranged below said superheating chamber, the burner tube of said burner being threaded through the bottom plate of said casing; and a casing for said burner.
8. The combination with a casing, of a supporting casting arranged in the upper end of said casing, said casting comprising a discharge chamber; an inwardly-projecting annular flange at the bottom of said discharge chamber; an inverted conical superheating chamber having an outwardly-projecting flange at its upper end arranged on said flange in said discharge chamber, said superheating chamber being adapted to be removed through the top of said discharge chamber; a threaded member for clamping said superheating chamber in position, said threaded member being provided with an opening for connecting said superheating chamber to said discharge chamber, and with an annular delivery passage; a plurality of ports connecting the said delivery passage to said superheating chamber; and heating coils arranged about said superheating chamber and connected to deliver to said annular delivery passage.
9. The combination with a casing having a closed bottom and having a discharge flue at its upper end, of a discharge chamber arranged in the upper end of said casing; an inverted conical spirally-corrugated superheating chamber arranged below and connected to deliver to said discharge chamber; an inverted conical baffle open at its lower end arranged in said superheating chamber; heating coils arranged about said superheating chamber; an annular connecting passage for said heating coils to said superheating chamber, said passage having a plurality of delivery ports; a burner arranged below said superheating chamber, the burner tube of said burner being threaded through the bottom plate of said casing; and a casing for said burner.
10. The combination with a casing having a discharge flue at its upper end, of a discharge chamber arranged in the upper end of said casing; an inverted conical spirally-corrugated superheating chamber arranged below and connected to deliver to said discharge chamber; an inverted conical baffle open at its lower end arranged in said superheating chamber; heating coils arranged about said superheating chamber; an annular connecting passage for said heating coils to said superheating chamber, said passage having a plurality of delivery ports; and a burner arranged below said superheating chamber.
11. The combination with a casing having a closed bottom and having a discharge flue at its upper end, of a discharge chamber arranged in the upper end of said casing; an inverted conical superheating chamber arranged below and connected to deliver to said discharge chamber; an inverted conical baffle open at its lower end arranged in said superheating chamber; heating coils arranged about said superheating chamber; an annular connecting passage for said heating coils to said superheating chamber, said passage having a plurality of delivery ports; a burner arranged below said superheating chamber, the burner tube of said burner being threaded through the bottom plate of said casing; and a casing for said burner.
12. The combination with a casing having a discharge flue at its upper end, of a discharge chamber arranged in the upper end of said casing; an inverted conical superheating chamber arranged below and connected to deliver to said discharge chamber; an inverted conical baffle open at its lower end arranged in said superheating chamber; heating coils arranged about said superheating chamber; an annular connecting passage for said heating coils to said superheating chamber, said passage having a plurality of delivery ports; and a burner arranged below said superheating chamber.
13. The combination with a casing having a closed bottom and having a discharge flue at its upper end, of a discharge chamber arranged in the upper end of said casing; an inverted conical spirally-corrugated superheating chamber arranged below and connected to deliver to said discharge chamber; heating coils arranged about said superheating chamber; an annular connecting passage for said heating coils to said superheating chamber, said passage having a plurality of delivery ports; a burner arranged below said superheating chamber, the burner tube of said burner being threaded through the bottom plate of said casing; and a casing for said burner.
14. The combination with a casing having a discharge flue at its upper end, of a discharge chamber arranged in the upper end of said casing; an inverted conical spirally-cor-

15. A superheating chamber arranged below and connected to deliver to said discharge chamber; heating coils arranged about said superheating chamber; an annular connecting passage for said heating coils to said superheating chamber, said passage having a plurality of delivery ports; and a burner arranged below said superheating chamber.
19. 15. The combination with a casing having a closed bottom and having a discharge flue at its upper end, of a discharge chamber arranged in the upper end of said casing; an inverted conical superheating chamber arranged below and connected to deliver to said discharge chamber; heating coils arranged about said superheating chamber; an annular connecting passage for said heating coils to said superheating chamber, said passage having a plurality of delivery ports; a burner arranged below said superheating chamber, the burner tube of said burner being threaded through the bottom plate of said casing; and a casing for said burner.
25. 16. The combination with a casing having a discharge flue at its upper end, of a discharge chamber arranged in the upper end of said casing; an inverted conical superheating chamber arranged below and connected to deliver to said discharge chamber; heating coils arranged about said superheating chamber; an annular connecting passage for said heating coils to said superheating chamber, said passage having a plurality of delivery ports; and a burner arranged below said superheating chamber.
30. 17. The combination with a casing, of an inverted conical spirally-corrugated superheating chamber; an inverted conical baffle open at its lower end arranged in said superheating chamber; heating coils arranged about said superheating chamber; an annular connecting passage for said heating coils to said superheating chamber, said passage having a plurality of delivery ports; and means for delivering heat to said superheating chamber and coils.
35. 18. The combination with a casing, of an inverted conical superheating chamber; an inverted conical baffle open at its lower end arranged in said superheating chamber; heating coils arranged about said superheating chamber; an annular connecting passage for said heating coils to said superheating chamber, said passage having a plurality of delivery ports; and means for delivering heat to said superheating chamber and coils.
40. 19. The combination with a casing of an inverted conical spirally-corrugated superheating chamber; heating coils arranged about said superheating chamber; an annular connecting passage for said heating coils to said superheating chamber, said passage having a plurality of delivery ports; and means for delivering heat to said superheating chamber and coils.
45. 20. The combination with a casing, of an inverted conical superheating chamber; heating coils arranged about said superheating chamber; an annular connecting passage for said heating coils to said superheating chamber, said passage having a plurality of delivery ports; and means for delivering heat to said superheating chamber and coils.
50. 21. The combination with a casing, of an inverted conical spirally-corrugated superheating chamber; an inverted conical baffle open at its lower end arranged in said superheating chamber; heating coils arranged about said superheating chamber and connected to deliver to the upper end thereof; and means for delivering heat to said superheating chamber and coils.
55. 22. The combination with a casing, of an inverted conical superheating chamber; an inverted conical baffle open at its lower end arranged in said superheating chamber; heating coils arranged about said superheating chamber and connected to deliver to the upper end thereof; and means for delivering heat to said superheating chamber and coils.

In witness whereof, I have hereunto set my hand and seal in the presence of two witnesses.
